UNITED STATES PATENT OFFICE.

SAMUEL G. BUSKARD, OF HAMILTON, ONTARIO, CANADA.

SMOOTHING-IRON.

970,788.

Specification of Letters Patent. Patented Sept. 20, 1910.

Application filed January 3, 1910. Serial No. 535,981.

To all whom it may concern:

Be it known that I, SAMUEL G. BUSKARD, a subject of the King of Great Britain, and resident of Hamilton, in the county of Wentworth, in the Province of Ontario, Canada, have invented new and useful Improvements in Smoothing-Irons, of which the following is a specification.

My invention relates to improvements in smoothing irons, and more particularly that class of irons for use by tailors and garment workers in general.

The objects of my invention are first, to provide a smoothing iron adapted to be heated by steam passing through a flexible steam tube connected to the rear end of the iron; second, to provide means whereby steam may be discharged from the smoothing face of the iron, thereby avoiding chilling the iron, and also avoiding the glossing of the cloth; third, to afford means whereby the steam issuing from the face of the iron may be instantly controlled, and independently cut off; fourth, to afford facilities for heating and moistening the garment being ironed without the aid of water or a sponge. I attain these objects by the mechanism illustrated in the accompanying drawing in which—

Figure 1 is an elevation of the smoothing iron. Fig. 2 is a sectional plan of the same. Fig. 3 is a sectional end elevation of the iron through the broken vertical line A. A. of Fig. 2, of the drawing. Fig. 4 is a sectional end elevation of the iron through the broken vertical line B. B. of Fig. 2 of the drawing. Fig. 5 is a sectional end elevation of the iron through the broken vertical line C. C. of Fig. 2 of the drawing. Fig. 6 is an enlarged detail elevation of a part of the steam entrance and valve to the smoothing iron and to the perforations in the face of the iron.

Similar letters refer to similar parts throughout the several views.

In the drawing D. is a hollow smoothing iron having a cover E., fitting snugly thereon and rigidly secured thereto by means of flanges 2, which fit snugly in the iron, and secured thereto in the usual manner.

F. is asbestos secured on the inner side of the cover to prevent the same from heating.

H. is the handle secured to the cover by means of its end supports 3 and screws 4.

The rear end support 3 has a slot 5 to allow the lever J. to operate therein, said lever is

fulcrumed on a transverse pin 6, in the support 3, and in said slot 5. On the rear end of the hollow iron is a gland box 7, the rear end of which has a gland 8, and a flexible steam tube K. forms a part of the gland or collar 8, and is for the purpose of securing the flexible tube to and in the gland box 7. In the interior, or chamber, 9 of the iron, and in proximity to the rear end thereof, is a hollow transverse bridge or passage M., which communicates with the longitudinal open ended steam channels or ways N. in the lower part of the iron, and forming a part of the same.

O. are a plurality of transverse steam passages or ways in the lower part of the steam chamber 9, forming a part of the iron and communicating with the longitudinal steam channels N. P. are a plurality of small holes, or perforations, extending from the passages N. and O. to and through the face of the iron. The perforations P. may be drilled with a very fine drill through the face of the iron to communicate with the steam channels and with the steam ways, to allow the discharge of steam through said perforations to the cloth being ironed. A greater number of the perforations P. may be used than those shown in Fig. 2 of the drawing, also a greater number of transverse steam ways O. may be used if deemed necessary to answer the purpose of the iron. The purpose of the perforations P. is to allow the steam to pass through to moisten the cloth while ironing the same, and previous to the ironing operation, when desirable.

R. is a hollow neck, extending rearward from the hollow bridge M. to proximity to the inserted end of the steam tube connection K., and near enough to allow a steam passage 12 around the neck R. to the hollow smoothing iron to heat the same, independently of the steam entering the neck R.

A small valve S., shown in Fig. 6 of the drawing, is located in the neck R., and is shown closed in its seating 13 in said neck. The upper end of the vertical stem 10 of the valve is pivotally connected to the lever J., which is within touch of the hand when on the handle of the iron.

By slight pressure by the hand on the lever J. the valve is consequently raised and thereby opened, and the steam then passes from the tube K. into the neck R., thence through the valve and into the bridge M.,

and into the channels, the steam ways and through the perforations.

5 T. is a spring on the cover of the iron adapted to press upward the lever J. on its fulcrum 6, in order to lower the valve S., and close the same, thereby preventing any possibility of the steam entering the neck R., consequently cutting off steam communication with the perforations P.

10 Other mechanical methods than the one shown may be employed for heating the hollow smoothing iron independently of supplying steam to the steam channels N., and the steam ways O., or supplying steam to the 15 hollow iron conjointly with said channels and ways.

The principal object of my invention is to supply steam to enter the smoothing iron to independently heat the same, and to supply 20 steam to pass through the perforations in the bottom, or face, of the iron, that said steam may moisten and heat the cloth being ironed.

25 What I claim as my invention and desire to secure by Letters Patent is:—

1. A hollow smoothing iron having a perforated bottom, a cover on the iron, open ended channels, having a neck, in the iron, transverse steam ways communicating with 30 the channels, said channels and ways communicating with the perforated bottom, a flexible steam pipe secured to the rear end of the iron and adapted to convey steam into the hollow iron, a valve in the said neck, and 35 means connected to the valve whereby steam from the flexible tube may be admitted into said neck and cut off from the same.

2. A smoothing iron having a chamber and perforations through the bottom of the 40 iron, a cover on the iron, a handle secured

on the cover, steam channels in the chamber, steam ways communicating with the channels, said perforations communicating with said channels and ways, a flexible steam tube secured to the rear end of the iron and 45 adapted to feed the chamber with steam, means on the steam channels to admit steam from the flexible tube and from the chamber, and means to cut off the steam from said channels, thereby excluding the steam from 50 the perforations.

3. In a smoothing iron, an iron having a chamber and perforations through the bottom thereof, steam channels, or ways, in said chamber communicating with said perforations, a flexible tube connected to the iron and adapted to admit the ingress of steam into the chamber thereof, to heat the iron, and means connected to the iron to admit steam from the chamber into said steam 60 channels, or ways, and means to control and to cut off the steam from said channels or ways.

4. In a smoothing iron, an iron having a plurality of perforations through the bottom thereof and a chamber, a plurality of steam ways in the chamber, said perforations communicating with said steam ways, a flexible tube connected to the rear of the iron and adapted to supply steam to said 70 chamber, means to admit steam from the chamber into said steam ways, and means connected to the steam ways, and to the iron for cutting off the supply of steam to said steam ways.

SAMUEL G. BUSKARD.
